JOSEPH OSCAR BISSONNETTE, OF HONOLULU, TERRITORY OF HAWAII, ASSIGNOR OF
ONE-HALF TO JAMES ALEXANDER MALLOY, OF HONOLULU, TERRITORY OF HAWAII

ATTACHMENT FOR INTERNAL-COMBUSTION ENGINES

Application filed February 27, 1929. Serial No. 343,150.

This invention relates to improvements in internal combustion engines, one object of the invention being the provision of air admitting means for connection to the air intake of 5 a carbureter and to the crank case of an internal combustion engine and adapted to be disposed behind the radiator and in front of the fan, and provided with a filtering means for preventing any particles of dust, dirt or other foreign matter carried by the air from entering the same, so that the air blast from the fan may cause the heavier particles to be precipitated or blown away, thus insuring the supply of clean 10 air to the air intake of the carbureter and clearing the crank case of objectionable vapors.

Another object of the present invention is the provision of a device of this character 20 which may be readily positioned in place and is so constructed that various modifications thereof for drawing oil vapor from the crank case of an internal combustion engine and delivering it together with air to the proper 25 places adjacent the exhaust and intake of the engine may be made according to the type of engine upon which same is to be used, and which is simple and inexpensive in construction and thoroughly efficient and economical 30 in use.

In the accompanying drawings:—

Figure 1 is a top plan view of one form 35 of air admitting device;

Figure 2 is a front elevation thereof;

Figure 3 is a section taken on the line 3—3 of Figure 1;

Figure 4 is an end elevation of the device as shown in Figure 2;

Figure 5 is a view similar to Figure 1 of a 40 modified shape of air admitting device;

Figure 6 is a view in elevation thereof;

Figure 7 is a section taken on the line 7—7 of Figure 5;

Figure 8 is an end view of the device as illustrated in Figure 6;

Figure 9 is a perspective view of the device as illustrated in Figure 5;

Figure 10 is a diagrammatic perspective 50 view of an automobile radiator with the device as shown in Figure 1 in position thereon;

Figure 11 is a diagrammatic top plan view of an internal combustion engine and radiator with the present device in operable relation thereto;

Figure 12 is a diagrammatic sectional view 55 taken on the line 12—12 of Figure 11.

Referring to the drawings, A designates the air admitting member, which, as shown in Figs. 1, 2 and 10, is rectangular in plan while that shown in Figs. 5, 6 and 9 is an 60 elongated member rounded at its ends.

The member A has an opening extending substantially the whole length of its rear wall and covered by a material S, such as perforated chamois or the like, which will permit the admission of air into the chamber A but will filter all particles carried thereby, so that oil vapor drawn through the conduit C at one end of the chamber A and filtered air drawn through the screen S will be delivered to the carbureter through the conduit C' at the other end of the chamber. When the present device is in use a member A is attached to the rear of the radiator K at a point directly in line with the axis of the fan J, which, as is usual, is operated by the engine P.

According to one embodiment of the present device the pipe or conduit C is connected to the breather tube G, which is sealed by an airtight lid H, while the pipe or conduit C' is connected to the super-heater chamber D surrounding the exhaust pipe E of the engine, from which chamber air passes the extension pipe F through to the intake of the carbureter (not shown). Thus clean air will be supplied to the carbureter and to the crank case and the carbureter will receive the vapors coming from the crank case through the pipe C.

It will thus be seen that with the chamber A in line with the fan J, as illustrated, the fan, when operating, will cause a suction of the air through the radiator and around the member A and that the heavier particles of dust in the air passing in front of the screened opening of the member A will be precipitated by the action of the fan so that the air drawn into the member A through the screen S will be freed of all of the particles that would

be deleterious to the bearings of the engine and to the carbureter and cylinders of the engine, the combined action of the filter screen S and the fan J insuring the delivery to the carbureter through the conduit C' of oil vapor drawn from the crank case through the conduit C and thoroughly cleansed or filtered air drawn through the screen S.

It is evident that many variations of the installation of the present device for delivery of the air to the carbureter or to the crank case may be constructed without departing from the spirit of the invention, the main idea of which is to use the member A and its screen S in conjunction with the fan J.

What is claimed as new is:

1. An apparatus of the character described, comprising a hollow member having an air admitting opening in one of its walls and a passageway adjacent each of its ends for connection, respectively, to the carbureter and to the crank case of an internal combustion engine, and an air-filtering screen covering said air admitting opening, said apparatus being adapted to be mounted adjacent to and in advance of the cooling fan of the engine with its air admitting opening directed toward said fan to permit the fan to assist in removing foreign particles from the air admitted to said air-admitting opening.

2. A device of the character described, including a relatively flat hollow member adapted to be mounted between the radiator and the cooling fan of an internal combustion engine and having in its wall which is directed toward the fan an opening substantially the full length thereof, an air filtering means over said opening, and a pair of nozzles projecting rearwardly from said hollow member, one adjacent one end of said hollow member for connection to and for receiving oil vapors from the crank case of an engine and the other adjacent the opposite end of said hollow member for connection to the carbureter of the engine.

In testimony whereof I have affixed my signature.

JOSEPH OSCAR BISSONNETTE.
